UNITED STATES PATENT OFFICE.

FRANK B. DAVIDSON, OF BROOKLYN, NEW YORK, ASSIGNOR TO HOWE AND DAVIDSON COMPANY, A CORPORATION OF NEW JERSEY.

PAPER BOX.

SPECIFICATION forming part of Letters Patent No. 756,478, dated April 5, 1904.

Application filed March 1, 1901. Serial No. 49,442. (No model.)

To all whom it may concern:

Be it known that I, FRANK B. DAVIDSON, of Brooklyn, in the county of Kings and State of New York, have invented certain new and useful Improvements in Paper Boxes; and I do hereby declare that the following is a full, clear, and exact description thereof, reference being had to the accompanying drawings, and to the letters of reference marked thereon, which form a part of this specification.

This invention relates to improvements in paper boxes of that class in which the bottom, side, and end walls of the box are formed from a single flat blank or sheet and in which the side and end walls of the box are held or confined in proper relation with respect to each other and to the bottom wall by means of integral overlapping parts or flaps on the said side and end walls which are detachably interlocked at the corners of the box.

The invention consists in the matters hereinafter described, and more particularly pointed out in the appended claims.

In the drawings, Figure 1 is a plan view of a scored and cut blank from which the bottom, end, and side walls of a rectangular box are made. Fig. 2 is an outside perspective view of one of the corners of the box when folded. Fig. 3 is an inside perspective view of the parts shown in Fig. 2. Fig. 4 is a fragmentary plan section of one corner of a modified form of blank. Fig. 5 is an inside perspective view of the corner of a folded box made up from the blank shown in Fig. 4. Fig. 6 is an outside view of the wall of the box with which the brace-flap is engaged.

First referring to the construction shown in Figs. 1 to 3, inclusive, A designates a rectangular blank which is scored along the lines a a' parallel with the margins of the side and end walls, respectively, of the blank to form the bottom, side, and end walls a^2 a^3 a^4 when said side and end walls are folded upwardly into their final positions. The side and end walls at each corner of the box are joined in their folded positions by means of flaps B' C' on the side and end walls, respectively, said flaps being formed from the material of the blank located within lines forming prolongations of

the side and end margins of the blank, so that the latter may be cut from rectangular stock without waste, such as would result if the flaps projected outside of the said side and end margins. Said corner of the blank is divided to form said flaps B' C' by two straight cuts, one bisecting the outer angle formed between the intersecting score-lines a a' and the other extending from the outer end of said oblique cut to the end margin of the blank parallel with the side margin thereof. This construction provides on the end of the flap B' a locking-tongue b , which is notched on its outer side edge to provide a laterally-directed prong b' , forming a hooked locking-head. The end wall a^4 of the box is provided with an angular slit c , which is adapted to receive the tongue b when the parts of the box are folded together, and said tongue is obliquely cut away at b^2 to permit the tongue to pass freely through said slit. The side wall of the box is provided with a slit b^4 of looped or U form, the ends of which are located one above the other and in a vertical or nearly vertical line. Said slit b^4 forms a tongue or ear b^3 , the free end of which projects toward the tongue b or toward the corner of the box.

In setting up a box made from the blank described the end walls a^4 and the flaps C' thereof are folded upwardly, and said flaps C' are each folded at right angles to its attached wall and parallel with the score-lines a' . The side walls a^3 are thereafter folded upwardly into position outside of the flaps C' in overlapping relation therewith and with their flaps B' folded outside the end walls a^4 of the box, and the tongues b thereof are passed through the locking-slits c to lock said flaps in place. Before the flaps B' have been locked in the manner described the end margins c' of the flaps C' are interlocked with the tongues b^3 on the side walls of the box by inserting said margins between said tongues and the side walls. To accomplish this result, the said tongues are pushed inwardly from the outside by the finger at the time the side walls are folded upwardly into their set-up positions, so that said margins c' of the flaps C' may be introduced between

the same and their connected walls, and the said margins will engage the ends of the slits b^4 . It will be noted that the angular locking-slits c are made of a size to permit 5 the prongs b' of the locking-tongues b to pass therethrough when said locking-tongues and connected flaps are slightly depressed, and when said prongs have passed through the 10 slits they spring back to their proper positions, with the ends of the prongs above the horizontal parts of the slits and with the inclined inner surfaces of the prongs engaging the inclined parts of said slits, as indicated in Fig. 3. When the box has been set up in 15 the manner described, it will be noted that the flap B' serves as a locking-flap to prevent both the side and end walls from moving outwardly and that the flap C' serves, in connection with the tongue b , as a brace to prevent 20 inward distortion or collapse of the box when pressure is applied to the end wall thereof in a direction to force the same inward.

The construction shown in Figs. 4 and 5, the margin c' of the flap C' is provided about 25 midway of its length with a short locking projection c^2 , which when said margin is interlocked with the tongue or ear b passes outwardly through the space between the ends of the slit b^4 , by which said tongue or ear 30 is separated from the connected wall. Said locking projection is made of approximately the same width as the depth of said opening, so that when engaged therewith it comes in contact with the ends of the U-shaped slit and 35 prevents vertical movement of the flap C' relatively to the side wall of the box, thereby giving additional strength and rigidity to the corners of the box and preventing dislocation of the parts. In this construction also the 40 oblique margin c^3 of the flap C' diverges between its ends from that shown in Fig. 4 in a manner to elongate the margin c' of said flap. When the margin c' of the flap is thus elongated, the locking projection may be arranged 45 at a greater distance from the top edge of the box, and the tongue b on the side wall a^3 of the box may be located at a correspondingly greater distance from the upper margin of the box than in the construction shown in 50 Figs. 1, 2, and 3.

My improvement described affords simple means for constructing boxes of this character and at the same time provides a connection between contiguous side and end walls of the 55 box of great strength and durability. The engagement of the tongues or ears b with the flaps C' effectually prevents inward movement or collapsing of the end walls of the box, and outward movement of the end walls is prevented by the overlapping and interlocking engagement of the flap B' therewith. It will be observed that the interlocking flaps at the 60 corner of the box form a double thickness of paper extending the entire length of the 65 corner, thereby making the corners strong

and rigid and enabling them to withstand rough usage—such, for instance, as the box being dropped and striking on its corner. In the construction described, moreover, there are no projecting flaps or tongues exposed at 70 the outer surface of the box in a manner to be torn off in the handling of the same.

A further advantage of the construction herein shown is that the locking and brace flaps are located entirely within the limits defined by the side and end margins of the blank, so that great economy is observed in producing the blank. Moreover, it will be noted that the locking and brace flaps are of such form that no part of the blank is cut away between the same in forming the flaps, so that practically all of the material within the area of the blank defined by the side and end margins thereof is retained, with the result of added rigidity in the set-up box.

My improvements are especially adapted for application to rectangular suit-boxes and boxes for analogous uses; but it is obvious that they may be applied to boxes or receptacles of other contour and for other uses.

While I have shown in the accompanying drawings a blank for the body of a box, it will of course be understood that a box-cover may be similarly constructed.

I claim as my invention—

1. As a new article of manufacture, a knock-down box, each corner of which comprises a double inner lock composed of two flaps, one having a hooked locking-head which is passed from the outside through a side slit adjacent to each corner so that the hooked head will be located in the box and will resist internal pressure, and the other flap engaging within the box behind an ear cut from that side of the box carrying the first-named flap and adjacent to each corner so that external pressure tends to move such parts into further engagement, substantially as and for the purposes set forth.

2. A blank for a knockdown box having at each corner a flap with a hooked locking-head, an angular slit adjacent to the corner with which said head is adapted to engage, a second flap, and an ear cut from that side of the box carrying the first-named flap and extending in the direction of the corner and behind which the second flap engages, substantially as and for the purposes set forth.

3. A blank for a knockdown box having at each corner a flap with a hooked locking-head, a slit adjacent to the corner with which the flap is adapted to engage, a second flap, and a U-shaped slit forming an ear which extends in a direction toward the corner, and behind which the second flap engages, said second flap being provided at its end with a projection of approximately the same width as said ear and which is adapted to enter the U-shaped slit and to have interlocking connection at its side edges with the ends of said U-shaped slit.

4. A blank for a knockdown box adapted to form a bottom, side and end walls, the ends of said side and end walls at each corner of the box being provided one with a flap provided with a hooked locking-head and the other with a slit with which the flap is adapted to engage, a second flap, and a U-shaped slit forming an ear which extends toward the corner, and behind which the second flap engages, said flaps being formed by means of an indirect cut which in its inner part is oblique and at its

outer part is perpendicular to the side of the blank which it intersects.

In testimony that I claim the foregoing as my invention I affix my signature, in presence of two witnesses, this 13th day of February, A. D. 1901.

FRANK B. DAVIDSON.
